Attorney

UNITED STATES PATENT OFFICE.

EDGAR J. WEAVER, OF COLUMBUS, OHIO.

LOCKING DEVICE FOR SWITCH BOXES.

Application filed July 13, 1921. Serial No. 484,420.

To all whom it may concern:

Be it known that EDGAR J. WEAVER, a citizen of the United States, residing at Columbus, in the county of Franklin and State 5 of Ohio, has invented certain new and useful Improvements in Locking Devices for Switch Boxes, of which the following is a specification.

This invention relates to improvements in 10 switch boxes or casings, of the type employed for the purpose of protecting switch and fuse mechanisms from being tampered with by unauthorized persons.

The primary object of the invention resides 15 in the provision of a switch box or casing of simple design and formation and wherein features of construction are embodied which will serve to prevent the main circuit controlling switch from being tampered 20 with without making the fact of the operation apparent upon inspection, the box being of such construction that access to the switch enclosed thereby can only be obtained by the fracture of a seal by means of which the box 25 is locked, the said seal thereby serving as a telltale to permit one to note at a glance whether or not the switch structure has been molested.

Another object of the invention resides in 30 forming the box or casing so as to include a switch compartment and a fuse compartment, access to the fuse compartment being obtainable by means of a pivot door structure, and the said door structure, in turn, 35 being locked in its closed position by means of a pivot plate member, the arrangement being such that the plate member must be oscillated to a position clear of the door structure to permit of the opening of the 40 latter, and when said plate member is in the latter position, the same will cooperate with the handle of the switch structure to open the same.

With these and other objects in view, as 45 will appear as the description proceeds, the invention accordingly consists in the novel features of construction, combinations of elements and arrangements of parts hereinafter to be fully described and particularly pointed out in the appended claims.

In the accompanying drawing, forming a 50 part of this specification, and in which similar characters of reference denote like and corresponding parts throughout the several 55 views thereof:

Figure 1 is a perspective view of the im-

proved switch comprising the present invention.

Figure 2 is a vertical longitudinal sectional view taken through the same.

Figure 3 is a horizontal sectional view taken through the box on the line 3—3 of Figure 2, and,

Figure 4 is a detail perspective view of the locking plate.

Referring more particularly to the details of the invention, the numeral 1 designates the improved switch box comprising the present invention. In the form of the invention specifically disclosed, the box is formed from sheet metal, and includes a rear wall 2, integral forwardly extending and vertically disposed side walls 3, a flat horizontal bottom wall 4, a similar top wall 5, and an open front 6, which is adapted to be closed by means of upper and lower door members 7 and 8 respectively. The door member 7 is also of a metallic construction, and has its upper end provided with a pair of ears 9, which are pivoted as at 10 in connection with upstanding flanges 11, integrally formed upon the upper edges of the side walls 3. The ears 9 constitute parts of side flanges 12, integrally formed with the door member 7, and when the latter occupies a closed position, its side flanges 12 will lie parallel with and immediately adjacent to the forward edges of the side walls 3. Similarly, the upper edge of the door member is provided with an inwardly extending flange 13, which is so disposed that when the door 7 is in its closed position, the said flange 13 will extend parallel with the top wall 5 of the box. This construction of the door 7 enables the latter to encase the edges of the box 95 that surround the open front 6, and thus a structure is provided which will be substantially water-tight. By pivoting the door 7 above the plane of the wall 5, the flanges 13 may be employed. The lower door member 100 8 is similar in construction to the upper door member, except that the lower door is pivoted as at 14 to the lower part of the box casing, and therefore swings downwardly, when being opened in contrast with the upward swinging movement which will be imparted to the door 7 when the latter is opened. The said lower door member also has its side and lower edges provided with flanges 15, which overlap the outer edges of 110 the side and bottom walls 3 and 4, the said flanges 15 cooperating with the flanges 12

and 13 to render the interior of the box water-tight.

The door 7 is employed to govern access to the fuse compartment 16, located within the upper part of the box, while the door member 8 is provided to render the switch compartment 17, formed in the lower part of the box, accessible, the said compartments being entirely independent of one another, so that while the fuse compartment 16 will be readily accessible at all times, the switch compartment will be permitted to remain in a locked condition, to which access cannot be had without destroying breakable parts or in marring the structure to such an extent that the access to the switch compartment will be clearly evidenced.

To this end, the upper edge of the door 8 is provided with an inwardly extending flange 18, the inner edge of which terminating in an upstanding longitudinally extending rib 19, which is normally positioned within the confines of the box proper. Extending adjacent to the rib 19, but in advance thereof is a locking rod 20. This rod is provided with an enlarged head 21 and with a threaded shank 22, the latter being disposed to be received within registering openings 23, provided in the side walls 3. The threaded end of the shank which protrudes beyond one of the side walls 3 is provided with a nut 24, capable of holding the rod against accidental displacement, and the extreme outer end of the shank 22 is provided with a frangible seal 25, by means of which the rod 20 cannot be withdrawn from its locking engagement, with respect to the rib 19, without the fact of its removal becoming apparent. It will be seen that when the rod is properly positioned, it will be impossible to pivotally move the lower door 8, and thus access to the switch compartment will be precluded. The top of the switch compartment is closed by means of a wall or partition 26, which is preferably formed from fiber, rubber or other insulating material, and extends completely across the interior of the box between the door 8 and the rear wall 2, the said partition underlying the flange 18 and is thereby locked, when the door 8 is closed, in active position, closing the top of the switch compartment. Within the box there is provided the usual insulating base 27, which is secured to the rear wall 2, the lower portion of said base being provided with the usual oscillating knife switch 28, which is adapted to have its operation governed by means of an exteriorly arranged handle 29. This handle is particularly shown in Figure 1, and includes at its outer end an arcuate hook 30 by means of which the handle may be grasped for manipulation in order that the switch may be thrown on or off. By this construction, it will be apparent that the operation of the switch may be readily controlled, but that the compartment 17 will be effectively closed to prevent tampering with the terminals of the switch itself. This condition will prevent wires from being surreptitiously attached to the switch structure and then led to points of use.

Pivots connected as at 31 with the upper portion of the door 8 is a pivot guard or locking plate 32. This plate, as shown, in Figure 1, is formed from sheet metal and is adapted when normally positioned to extend in front of the upper door 7, in order that the said latter door will be retained in its closed position. The plate 32 has one of its vertical edges provided with an inwardly extending flange 33, capable of lying contiguous to one of the side walls 3, and a projection 34 is provided on the plate beneath the flange 33, the said projection lying in the same vertical plane as the major portion of the plate. It will be seen that to open the door 8, for the purpose of obtaining access to the fuse compartment 16, it will first be necessary to oscillate the plate 32 so that its edge 35 will lie immediately beneath the lower edge of the door 7. When this is done, the door 7 will be released, permitting the same to be raised or lowered about its pivot 10 at will. However, it will be observed that the relationship between the projection 34 and the hooked end 30 of the handle 29 of the knife switch 28 is such that as the plate is oscillated outwardly to unlock the door 7, the said projection will engage with the hook 30, thereby causing the oscillation of the handle 29 and the consequent opening of the switch 28. Therefore, in view of this construction it will be manifest that the fuse compartment will not be accessible until the knife switch has been opened. This is a feature of safety which will prevent injury to unskilled persons when engaged in the act of adjusting or replacing the fuses 36 carried by the base 27 and located within the compartment 16.

From the foregoing description, it will be apparent that the present invention provides a switch box which may be efficiently utilized in protecting the electrical installations of public service companies from surreptitious or unauthorized actuation. By its use, the switch encased thereby may be freely operated, from an exterior position with respect to the casing, but that the terminals of the switch will be enclosed to prevent the attaching of wires or other current conveying devices thereto without furnishing some evidence of the fact of such use. Also, by means of the pivot plate 32, persons unfamiliar with the electrical apparatus may adjust or replace the fuses 36 without fear of shock or injury, because of the fact that the switch will be opened prior to the openings of the door 7. Then, the said plate will

also serve, as above specifically described, to prevent current from being drawn out of the box by way of the fuses and the door 7. The construction of the box is simple and 5 all parts thereof are capable of being substantially united so as to produce a structure capable of withstanding adverse weather conditions and to prevent the entrance of moisture or water into the casing proper.

10 10 What is claimed is:

1. A switch box comprising a casing having an open front, a partition disposed within said casing and dividing the latter into spaced fuse and switch compartments, pivot 15 door members for each of said compartments, locking means for retaining the door member of said switch compartment in a closed position, a frangible seal for said locking means, a switch disposed within said 20 switch compartment, an operating handle for said switch located exteriorly of said box, and a pivot guard plate normally arranged to maintain the door member of said 25 fuse compartment in a closed position, said plate serving upon oscillation to engage said switch handle to open said switch when said plate occupies a position permitting of the opening of the door member of the fuse compartment.
- 30 2. A switch box comprising a casing including an open front, a partition located within said casing and dividing the latter into spaced fuse and switch compartments, pivot door members for each of said compartments, said door members being adapted to close the open front of said casing, a lock-

ing mechanism for the door member covering the switch compartment, a switch operating handle located exteriorly of said casing, and a guard member pivotally mounted 40 on the door member of the switch compartment and cooperative with the upper door member for retaining the latter in a closed position, said guard member serving to engage the operating handle of said switch 45 mechanism so that the latter will be opened whenever the guard member assumes a position permitting of the opening of the door member covering said fuse compartment.

3. A fuse box comprising a casing having 50 an open front, a partition located within said casing and dividing the latter into spaced fuse and switch compartments, door members pivotally connected with said casing and arranged to cover the front of said 55 casing, a switch located within said switch compartment, an operating handle for said switch extending exteriorly of said casing, and a pivot guard member carried by the door member of said switch compartment 60 and normally disposed to prevent the opening of the door member of the fuse compartment, said guard member having a horizontal flange carried thereby arranged for co-operation with said switch handle, whereby 65 when the guard member is moved to a position permitting of the opening of the door of said fuse compartment, said switch will occupy an open position.

In testimony whereof I affix my signature.

EDGAR J. WEAVER.
